UNITED STATES PATENT OFFICE.

WILLIAM O. INAMI, OF LOS ANGELES, CALIFORNIA.

ADJUSTABLE RACK.

1,216,321.

Specification of Letters Patent. Patented Feb. 20, 1917.

Application filed March 31, 1915. Serial No. 18,263.

To all whom it may concern:

Be it known that I, WILLIAM O. INAMI, a subject of the Emperor of Japan, residing at Los Angeles, in the county of Los Angeles and State of California, have invented 5 a new and useful Adjustable Rack, of which the following is a specification.

This invention relates to improvements in racks or reading rests for supporting books 10 and the like, or music, and resides in the provision of a rack which may be easily and quickly attached to the arm of a chair or like support and may be adjusted to suit the person sitting in the chair, so that the 15 article supported on the rack will be in the proper position.

Another object is to provide vertically adjustable rotatable means for detachably securing the rack to a chair or the like.

20 A further object is to provide easily operable, reliable means to vertically adjustably and slidably support the rack upon the vertically adjustable rotatable means, so as to provide a plurality of adjustments.

25 A still further object is to provide laterally adjustable means to clamp a book or the like in open position on the rack, said means being extensible to accommodate books of various sizes.

30 A yet further object is to provide a device of the above-mentioned character which is of simple construction, is reliable and efficient in operation and may be cheaply manufactured.

35 The invention consists in certain novel features of construction and combinations, and arrangements of parts as will be more fully hereinafter described and pointed out in the claim.

40 In the drawings:

Figure 1 is a perspective view of my improved rack showing it attached to a chair and supporting a book;

Fig. 2 is a front elevation of the rack re- 45 moved from a chair;

Fig. 3 is a horizontal sectional view taken on line 3—3 of Fig. 2;

Fig. 4 is an enlarged vertical sectional view taken on line 4—4 of Fig. 2; and

50 Fig. 5 is a rear elevation of my improved

rack showing it mounted upon a stand constructed for supporting music.

Referring to the drawings by characters of reference, 1 designates as an entirety, means for vertically adjustably and slidably supporting the book or other article supporting frame, said means comprising a vertically adjustable rod 2 which is rotatably and slidably mounted within a split sleeve 3 carried upon clamping means 4. A set screw 5 is carried by the split sleeve 3 and provides means for tightening the sleeve upon the rod to hold the rod in adjusted position. The clamping means 4 comprises a U-shape frame 6 through one side of which is mounted a tightening screw 7. A clamping plate 8 is carried on the inner end of the tightening screw 7 and is arranged to coöperate with a similar plate 9 fixed to the inner face of the opposed side 70 of the frame 6. These plates 8 and 9 may be provided with felt gripping surfaces to prevent injury to the article to which the clamp is attached.

A horizontal rack supporting rod 10 is 75 extended at right angles to the rod 2 and upon one end carries an elbow 11. The lower end of the elbow is formed with a squared socket to receive the squared upper end of the rod 2. By this arrangement the rod 10 is pre- 80 vented turning relative to the rod 2.

Mounted for sliding movement upon the rod 10 is means for vertically adjustably supporting a skeleton book or other article supporting frame 14. This means comprises 85 a substantially upright plate 15 which has its lower end bent to form a substantially rectilinear sleeve 16. This sleeve 16 is slidably mounted upon the rod 10, the rod being rectilinear in cross section. The inner face 90 of the plate 15 is provided with a series of rack teeth 17, and said plate engages with the rear face of one of the frame members 18 of the frame 14. A guide 19 is mounted upon said frame 14 and receives the plate 15. 95 Guide fingers 20 are carried on the free end of the plate 15 and slidably engage with the frame member 18. A spring finger or catch 21 is secured upon the frame 14 and has one end arranged for engagement with the rack 100

teeth 17. This finger 21 is arranged so that the frame 14 may be pushed upwardly freely but will catch with the teeth 17 and hold the frame in adjusted position. The finger is bowed intermediate its ends so as to project outwardly from the frame 14 and permit of its being readily grasped and pulled out of engagement with the teeth 17.

The frame 14 is substantially rectangular and comprises substantially upright side bars 22 and bottom and top bars 23 and 24 that are secured at their ends in any suitable manner to the bars 22. The frame member 18 is secured to the bars 23 and 24 centrally of the ends of said bars and is disposed parallel to the bars 22. The lower bar 23 is provided with an outwardly extending relatively large book or other article supporting flange 25 and the book or other article supported by the frame 14 rests on said flange 25.

An electric lamp 26 and reflector 27 are secured in any suitable manner upon the upper bar 24 of the frame 14 and the reflector is arranged to throw the light from the lamp upon the book or other article supported on said frame.

Mounted upon the frame 14 is adjustable extensible book or other article clamping means. This means comprises elongated plates 28 and 29 that are laterally slidably secured upon a supporting plate 30. The plate 30 is secured at its ends to the side bars 22 of the frame and between the bars 23 and 24. Longitudinal slots 31 are formed in the plate 30 on opposite sides of the center of said plate. Rivets, screws or other suitable fastening elements 32 are inserted through the plates 29 and extend through the slots 31. Washers or other suitable elements 33 are secured upon said fastening members 32 and prevent them from being pulled out of the slots 31, said elements 33 resting in engagement with the rear face of the plate 30. The outer ends of the plates 28 and 29 are offset as at 34 and pivoted to said offset ends are book or other article clamping plates 35. These plates 35 are relatively narrow and are pivoted each at one end to said ends 34. Pivoted upon the outer ends of the plates 35 are extensible clamping fingers 36, each of which comprises substantially parallel clamping portions 37, which portions are spaced from one another. When it is desired to hold a book or other article in open position upon the frame 14, both the plates 35 and fingers 36 are turned inwardly so as to bring the fingers 36 in engagement with the leaves of the book or article upon the frame, so as to hold the book or article in the desired position.

Mounted upon the frame 14 is means for laterally adjusting the book or other ar-

65 ticle clamping means and this means comprises operating links 38 and 39 each of which is pivoted at one end to fastening elements 40 that are carried by the plates 28 and 29 and extend through the slots 31. These links extend upwardly from the plates 28 and 29 and at their upper ends have a common pivot element 41 which is slidable in a longitudinal slot 42 formed in the frame member 18. The member 41 is provided with a head to be grasped to effect 70 the adjustment of the clamping means and is constructed so that it cannot be accidentally pulled out of the slot 42.

In operation when it is desired to hold a book in open position upon the frame 14, 80 as shown in Fig. 1 of the drawings, the plates 28 and 29 carrying the clamping means 35 and 36 are adjusted to the proper position by sliding the element 41 in the slot 42 in the proper direction and said 85 clamping elements 35 and 36 are moved into clamping position after the manner hereinbefore described. The clamping means 4 provides for the ready and reliable clamping to a chair or like support, and means 1 90 supported by the clamping means 4 may be vertically adjusted and swung into the right position. By means of the plates 15 and coöperating parts, the frame 14 may be vertically adjusted relative to the bar 95 10 so as to bring the book or article supported upon the frame 14 into the proper position suitable to the person sitting in the chair. The frame 14 may be slidably adjusted on the bar 10 and it will be seen that 100 in view of the various adjustments permitted it may be moved into the position most suitable to the person or reader sitting in the chair. With this device a book or other article may be supported without getting 105 in the way of the person sitting in the chair.

In practice I have found that the form of my invention illustrated in the drawings and referred to in the above description as the preferred embodiment is the most efficient and practical, yet realizing that the conditions concurrent with the adoption of my device will necessarily vary, I desire to emphasize the fact that various 115 minor changes in construction, proportion and arrangement of parts may be resorted to when required without sacrificing any of the advantages of my invention as set forth in the appended claim.

120 What I claim is:

A rack of the character described comprising an article supporting frame, a vertical rod, means to vertically adjustably and rotatably support said rod, means to secure 125 said last named means to a chair, a supporting rod connected with said rod and extending at right angles thereto, a plate

slidable on said rod and extending upwardly therefrom and having rack teeth on one face thereof, means to slidably connect the frame with the plate, and a spring catch carried by said frame and engaging said rack teeth, said spring catch being bowed outwardly intermediate its ends.

In testimony whereof, I have hereunto set my hand at Los Angeles, California, this 22d day of March, 1915.

WILLIAM O. INAMI.
